J. L. McQUARRIE

AUTOMATIC TELEPHONE SWITCH

Filed Dec. 15, 1920

Fig. 1

Fig. 2.

Inventor:
James L. McQuarrie
by Joel Ch. Palmer, Atty.

UNITED STATES PATENT OFFICE.

JAMES L. MCQUARRIE, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed December 15, 1920. Serial No. 430,896.

To all whom it may concern:

Be it known that I, JAMES L. MCQUARRIE, a citizen of the United States, residing at New York, in the county of New York, State 5 of New York, have invented certain new and useful Improvements in Automatic Telephone Switches, of which the following is a full, clear, concise, and exact description.

This invention relates to automatic 10 switches, and more particularly, to automatic switches of the type used in telephone exchanges.

The invention is an improvement upon applicant's U. S. Patent No. 1,290,616, issued 15 January 7, 1919.

It is the object of this invention to provide a switch of the type described in the above mentioned patent, which will serve a larger number of trunks or subscribers' lines without materially increasing the size of the 20 structure.

A feature of the present invention is the use of a contact bank of the panel type in connection with a switch of the well-known 25 "up and around" structure having arcuate rows of contacts on both sides, but situated in different sectors, so that a rotary sweep of the contact brushes first wipes over the contacts on one side of the bank and then 30 over the contacts on the other side. This arrangement doubles the number of lines available at one sweep of the contact brushes without increasing the width of the banks and only slightly increasing the thickness.

With reference to the accompanying 35 drawing, Fig. 1 is a plan view of one end of an automatic switch and Fig. 2 is an elevation, partly in section, showing a part of the switch, sufficient to illustrate the invention.

As in the switch described in U. S. Patent 40 No. 1,290,616, previously referred to, the present invention is shown embodied in a switch structure comprising two bank 45 groups, each consisting of a plurality of unit layers 1, between which are situated a number of rotatable and longitudinally movable brush rods 2. On each brush rod there is mounted two sets of contact brushes 7 and 8 respectively. The two sets of brushes are connected in multiple and are therefore electrically equivalent to a single set. One brush rod and its brushes are shown in the drawing, but it will be understood that there

would ordinarily be several brush rods, situated at intervals between the bank groups. 55

The unit layers 1 of the two bank groups may be vertically staggered with respect to each other, as illustrated, or, if desired, the unit layers in the two groups may be on the 60 same levels, that is, not staggered. Each unit layer comprises a plurality of longitudinally extending multiple conductors 3, each separated from the others by insulating strips 4. The conductors 3 are situated on 65 both sides of the unit layers, that is, top and bottom, and those on the top are separated from those on the bottom by the insulating strips 5.

At each brush position, each unit layer is 70 provided with two arcuate rows of contacts 6, one row on the top and the other on the bottom, the latter being shown in dotted lines in Fig. 1. There is a contact 6, at each brush position, for each conductor 3. The 75 two arcuate rows are situated in adjoining sectors and each extends through an arc of nearly 90°.

To select a unit layer, the brush shaft 2 together with brush sets 7 and 8 are moved 80 vertically to the desired level, the brushes being situated during that movement as shown in Fig. 1.

The brush shaft 2 is then rotated one way or the other, depending upon the unit layer 85 selected and the brush set 7 sweeps over and makes contact with the row of contacts on the upper side of the selected unit layer. If the desired set of terminals does not happen to be in the upper row, the brush shaft continues its rotation and the brush set 8 wipes over the lower row of contacts until the desired set is found whereupon the brush shaft stops. 90

The brushes shown in dotted lines in Fig. 95 2 are situated in line with a unit layer on the far side of the view, which is one vertical step lower than the position occupied by the brushes shown in full lines.

The mechanism for operating the switch 100 may be the same as that described in connection with the aforementioned U. S. Patent No. 1,290,616.

Practical consideration makes it desirable 105 to restrict the width of the unit layers 1 to a minimum and it will be seen that the arrangement described accomplishes that end, for with a given number of trunks or sub-

scribers' lines to be accommodated, the width of the unit layers is reduced by substantially one-half of that which would be required if the contact terminals 6 were situated on only 5 one side of the unit layer.

It has been mentioned in a previous paragraph that each unit layer 1 comprises a plurality of longitudinally extending multiple conductors 3 each separated from the other 10 by insulating strips 4. The necessity for these multiple conductors 3 prevents the contacts 6 from occupying the entire upper face of a unit layer since the characteristics of this switch require that the contacts be set 15 in arcuate rows, and in order to occupy the entire upper face of a unit layer the contacts would have to cover an arcuate path of 180°. It is apparent that such an arrangement of contacts would not be practical as 20 the contacts situated in one half of the 180° span would interfere with the multiple conductors 3 interconnecting an adjacent bank 25 of contacts and the contacts in the other half of the span.

From the foregoing, the desirability of placing the contacts on both sides of a unit layer, in 90° spans, is readily discernible.

What is claimed is:

1. In an automatic switch, a terminal bank 30 comprising a plurality of arcuate rows of contacts, all of said rows situated about a common center and each row in a different plane and different sector from the others.

2. In an automatic switch, a terminal bank 35 comprising two arcuate rows of contacts, both of said rows situated about a common center, each row in a different plane and different sector from the others.

3. In an automatic switch a terminal bank comprising a plurality of arcuate rows of 40 contacts, all of said rows situated about a common center, each row in a different plane and different sector from the others and a plurality of sets of contact brushes, one for the contacts in each plane, said brushes 45 adapted to be rotated simultaneously over said bank contacts, each set of brushes engaging the contacts in each respective plane during said rotation.

4. In an automatic switch, a flat terminal bank, contacts on both sides of said bank arranged in the same arc, the contacts on one side of said bank situated in one sector and the contacts on the other side of said bank 55 situated in another sector and two sets of rotatable contact brushes, one of said sets of brushes adapted to engage the contacts on one side of said bank and the other set of brushes adapted to engage the contacts on the other side of said bank.

5. In an automatic switch, a flat terminal bank, contacts on both sides of said bank arranged in the same arc, the contacts on one side of said bank situated in one sector and the contacts on the other side of said bank 60 situated in another sector, and a single operating member having two sets of rotatable contact brushes thereon, one of said sets of brushes adapted to engage the contacts on one side of said bank and the other set of 65 brushes adapted to engage the contacts on the other side of said bank.

In witness whereof, I hereunto subscribe my name this 14th day of December A. D., 1922.

JAMES L. McQUARRIE.
